UNITED STATES PATENT OFFICE.

THOMAS CUNNINGHAM, OF PHILADELPHIA, PENNSYLVANIA.

METHOD AND APPARATUS FOR STRETCHING AND PRESSING KNIT TUBULAR FABRICS.

1,401,589.

Specification of Letters Patent. Patented Dec. 27, 1921.

Application filed March 2, 1920. Serial No. 362,842.

To all whom it may concern:

Be it known that I, THOMAS CUNNINGHAM, a citizen of the United States, residing in Philadelphia, in the county of Philadelphia and State of Pennsylvania, have invented certain new and useful Improvements in Methods and Apparatus for Stretching and Pressing Knit Tubular Fabrics, whereof the following is a specification, 10 reference being had to the accompanying drawings.

The invention relates to the stretching and pressing of knit tubular fabrics into such form as to be capable of being conveniently handled subsequently, for cutting to garment lengths. On account of the characteristic flexibility of such fabrics, considerable difficulty has heretofore been experienced in preventing skewing or other irregularities when pressing the tube into a doubled flat web. As a consequence, proper registry of the corresponding wales of the opposite sides of the flattened tube could not be obtained. This lack of registry was a 20 serious drawback when the goods were cut, and especially in cutting goods having transverse stripes,—either of ornamental knitting or of variegated coloring,—intended for sweaters, bathing suits, etc.

I have found that these difficulties can be overcome by gradually and progressively expanding or spreading the fabric flat over a substantial linear extent to permit an initial automatic equalization of the tension therein, preferably moistening the fabric while thus expanded, and then stretching the fabric to the desired degree previous to pressing, the final stretching being so effected as to insure proper superposition of 30 the opposite sides of the flattened tube in being fed to the pressing devices.

The invention also comprehends certain other novel details of construction and arrangement which will be better understood 40 from the detailed description which follows.

In the accompanying drawings, Figure I, is a plan view, more or less diagrammatic, of a fabric stretching and pressing apparatus, conveniently embodying my invention.

Fig. II, is a longitudinal section on an enlarged scale, through a portion of the apparatus, the plane of the section being indicated by the arrows II—II in Fig. I.

55 Figs. III and IV, are detail cross sections

taken as indicated by the lines and arrows III—III, and IV—IV, in Fig. II.

Fig. V, is a perspective view of a portion of the frame by which the fabric is stretched.

Fig. VI, is a detail section showing the 60 manner in which the stretcher frame is adjustably connected at its ends, to anchorage links.

Fig. VII, is a detail section on an enlarged scale illustrating the method of 65 removably attaching the anchorage links for the stretcher frame to the end of the cylindrical support upon which the tubular fabric is initially mounted.

The apparatus shown comprises a supporting cylinder 1, upon which the tubular fabric "F," to be pressed, is initially mounted, and from which it is drawn over a spreader table comprehensively indicated at 2, under pull of a pair of pressing rolls 70 3 and 4. These rolls are conventionally shown as of the hollow steam heated type 75 ordinarily employed for this purpose, and may be intergeared for positive driving in any approved manner.

In the passage over the top of the spreader table 2, the feeding of the fabric is facilitated by a transversely extending auxiliary roller 5, which is driven directly from the trunnion of the pressing roll 4, by means of 80 a sprocket chain connection 6. Feeding is further facilitated by additional rollers 7 and 8, which are in turn rotated from the shaft of the auxiliary roller 5, through relay belt connections 9, 10 respectively, the 85 transmission system being so designed as to maintain substantially the same surface speed throughout the various moving parts 90 of the apparatus.

Associated with the auxiliary roller 5, is 95 a superimposed, gravity tension roller 11, which is journaled for free rotation in the ends of arms 12, 12, fulcrumed to brackets 13, 13, on the table 2. The tension roller 11, is driven by contact with friction collars 14, 100 14, on the ends of the roller 5 (see Figs. II and III) and the tension rolls 5 and 11 are also spaced apart by these friction collars.

The spreader table 2, is interrupted at one point as at 15, to accommodate a steam box 105 16, within which are housed perforated steam pipes 17, and 18, one above and the other below the line of travel of the fabric. By this means, the requisite amount of moisture is imparted to the fabric for a well 110

known purpose preparatory to final pressing between the rolls 3 and 4.

In the course of its travel through the apparatus, the fabric is drawn over a stretcher frame 20, which is of hoop form and preferably substantially elliptical in contour, (see Fig. IV). This frame operates within the tube, and is disposed transversely to the direction of feed in the interval between the presser rolls 3 and 4, and the auxiliary roller 5, as clearly shown in Figs. I and II. This frame is composed of a number of inter-pivoted segments including end segments 21, 22, and intermediate segments 23, 24. The end segments 21, 22, are respectively formed as integral parts of bars 25, 26, by which the frame structure is supported in a manner which will presently be described. The intermediate links 23-24, are composite in structure, and each comprises two sections 27, 28, which have their respective inner ends overlapped and secured by pivot bolts 29. The width of the frame as a whole may be varied by increasing or decreasing the extent of overlapping of the composite sections of the segments 23, 24, a number of screw holes being provided in the sections 27, 28, for selective co-operation with the bolts 29, for this purpose. By reason of the hoop form of the stretcher frame, a comparatively sharp continuous edge is afforded, which edge is intended to contact evenly with all portions of the inner surfaces of the fabric tube so as to impart uniform stretch thereto. The stretcher frame 20, is supported in the apparatus by having the integral bars 25, 26, of its segments 21, 22, bridged between the pressing roll 4, and the auxiliary roller 5. Thus it will be seen from Fig. II, that said bars have their forward ends engaged within the bight between the pressing rolls 3, 4, and their other ends, engaged in the interspace between the auxiliary feed roller 5, and the associated gravity tension roller 11, so that vertical displacement of the frame is, by this arrangement, prevented. In order to insure the stretcher against longitudinal displacement under pull of the fabric, it is tied by means of divergent anchorage links 30, hooked to the end of the supporting cylinder 1, previously referred to, as clearly shown in Figs I and VII. These anchorage links are preferably made of two interhooked sections so as to allow ample freedom for relative self adjustment under pull of the fabric, and also to permit similar freedom for self-centralization of the stretcher frame 20. Attachment of the links 30, to the frame is preferably effected as shown in Fig. VI, the link ends being forked as at 31, and the adjacent ends of the bridging bars 25, 26, of the frame 20, correspondingly reduced to fit in the forks. The effective length of the connections 30 can be adjusted to vary the position of the stretcher frame 20 between

the presser rolls 3, 4 and the tension rolls 5, 11 by inserting the studs 33 in the free ends of the spring prongs 35 through any one of a series of holes 36 in the bars 25, 26.

In practical operation, a standard length 70 of the tubular fabric to be pressed is first mounted upon the supporting cylinder 1, and thence drawn over the stretcher structure preparatory to being fed to the presser rolls 3 and 4, in the manner clearly shown in the 75 illustrations. The feeding is accomplished as before noted, by rotation of the presser rolls 3 and 4, with the assistance of the auxiliary tension rolls 5 and 11, and of the supplemental rolls 7 and 8. In the course 80 of its passage through the apparatus, the fabric is first gradually spread out or expanded flat through the action of the divergent anchorage links 30. This spreading, it will be noted, takes place over a substantial linear extent so as to permit an initial 85 automatic equalization of surface tension in the goods. The fabric, thus evenly spread, then passes through the steam box 16, and is moistened to the proper degree preparatory 90 to being drawn over the stretcher frame 20, under guidance of the rollers 5 and 11. By properly adjusting the relative positions of the several constituent segments of the frame, the tension imposed upon the inner 95 surface of the tube may be made uniform and the desired registry of the opposed layers entering between the rolls 3 and 4, thus obtained. After pressing, the fabric may be wound into bolt form in readiness 100 for subsequent cutting to garment lengths in the manner previously mentioned herein.

Having thus described my invention, I claim:

1. An apparatus of the character described, comprising presser rolls for pressing a tubular fabric flat; tension rolls between which the tubular fabric passes on its way to said presser rolls; and means for spreading apart the sides of the tube on 110 its way from said tension rolls to said presser rolls.

2. An apparatus of the character described, comprising a pair of pressing rolls; an auxiliary roller co-operating with said 115 pressing rolls in feeding a tubular fabric to be pressed; a stretcher frame over which the fabric is drawn, said frame being disposed at right angles to the direction of feed in the interval between said pressing rolls 120 and the co-operating auxiliary feed roller, and supported by attached bridging bars having their forward ends engaged within the bight between the pressing rolls, and their other ends resting on said auxiliary 125 roller; and means for preventing displacement of the stretcher under the pull of the fabric.

3. An apparatus of the character described, comprising a pair of pressing rolls; 130

- an auxiliary roller coöoperating with said pressing rolls in feeding a tubular fabric to be pressed; a gravity tension roller superimposed upon said auxiliary roller with provision of an interspace afforded by end collars upon said auxiliary roller; a stretcher frame over which the fabric is drawn, said frame being disposed at right angles to the direction of feed in the interval between the 5 pressing rolls and the coöoperative feed roller, and supported by attached bridging bars having their forward ends engaged within the bight between the pressing rolls and their other ends in the interspace between the auxiliary rolls and associated tension roller; and means for preventing displacement of said stretcher frame under the pull of the fabric.
4. An apparatus of the character described, comprising a cylindrical support adapted for the initial mounting of a tubular fabric, said support having its axis in the direction in which the fabric is to be fed; a spreading table; a pair of pressing 20 rolls by which the fabric is drawn over the top of the spreading table; an auxiliary roller coöoperating with said pressing rolls in feeding the fabric; a stretcher frame over which the fabric is drawn previous to 25 pressing; said frame being disposed at right angles to the direction of feed in the interval between said pressing rolls and the auxiliary feed roller; and anchorage links extending divergently over the top of the table from 30 the end of the cylindrical fabric support to the extremities of the stretcher frame, said links serving by virtue of their divergence, to effect a gradual spreading of the fabric previous to the final stretching.
5. An apparatus of the character described, comprising means for feeding a tubular fabric; and a transverse stretcher adapted to make contact evenly with all 35 portions of the interior surface of the fabric tube, along a comparatively sharp continuous edge only.
6. An apparatus of the character described, comprising means for feeding a tubular fabric; and a transverse stretcher frame of hoop form over which the fabric is drawn comprising a number of inter-pivoted segments, and capable of being expanded and contracted in different directions for adjustment of the tension thereby induced in different portions of the fabric. 45
7. An apparatus of the character described, comprising means for feeding a tubular fabric; in combination with a transversely disposed stretcher frame of elliptical hoop form over which the fabric is drawn, 50 said frame being composed of a pair of opposite end segments and a number of intermediate uniting segments capable of being expanded to permit adaptation of the frame to stretching fabric tubes of different 55 diameters.
8. An apparatus of the character described, comprising means for progressively expanding a tubular fabric flat; means for spreading apart and stretching the sides of the tube; and means for pressing the sides 60 of the tube flat together.
9. The method of stretching and pressing a tubular fabric, which consists in progressively expanding the fabric flat; spreading apart the sides of the tube to permit equalization of tension in the fabric; and pressing the sides of the tube flat together. 65
- In testimony whereof, I have hereunto signed my name at Philadelphia, Pennsylvania, this twenty-fifth day of February, 1920.

THOMAS CUNNINGHAM.
